UNITED STATES PATENT OFFICE.

ERNEST JAMES JOHNSON, OF STOKE-UPON-TRENT, ENGLAND.

DESIGN FOR A COVER-DISH.

46,738.

Specification for Design.

Patented Dec. 8, 1914.

Application filed October 8, 1914. Serial No. 865,762. Term of patent 3½ years.

To all whom it may concern:

Be it known that I, ERNEST J. JOHNSON, a subject of the King of Great Britain, residing at Stoke-upon-Trent, Staffordshire, England, have invented a new, original, and ornamental Design for a Cover-Dish, of which the following is a specification, reference being had to the accompanying drawing, forming part thereof.

Figure 1 is a plan view of a cover dish, showing my new design; and Fig. 2 is a side elevation of the same.

I claim:

The ornamental design for a cover dish as shown.

ERNEST JAMES JOHNSON.
